Atty's.

UNITED STATES PATENT OFFICE.

ROY H. SMITH, OF KENT, OHIO.

SOCKET WRENCH.

Application filed October 4, 1919. Serial No. 328,499.

To all whom it may concern:

Be it known that I, ROY H. SMITH, a citizen of the United States, residing at Kent, in the county of Portage and State of Ohio, 5 have invented a certain new and useful Improvement in Socket Wrenches, of which the following is a full, clear, and exact description.

This invention relates to socket wrenches 10 adapted particularly for setting and removing rim nuts of a demountable rim automatic wheel.

The object of the invention is to provide an efficient wrench which may be formed 15 from a straight rod or bar of iron, steel or other metal, with the ends of the rod forming handles for manipulating the wrench, and an intermediate portion of the rod doubled on itself to form the shank of the 20 closed end of which the wrench head is formed.

The invention may be briefly summarized as consisting in certain novel details of construction which will be described in the specification and set forth in the appended 25 claims.

In the accompanying sheet of drawings wherein I have shown two slightly different forms of a wrench, and also the preferable 30 way in which it is formed, Fig. 1 is a perspective view of a wrench embodied in my invention; Fig. 2 is a similar view showing a slight modification; Fig. 3 is a sectional view substantially along the line 3—3 of Fig. 1, 35 looking in the direction indicated by the arrows; Fig. 4 shows the manner in which a rod is first bent to form the wrench; Fig. 5 is a view illustrating the manner in which the head is upset on the shank of the wrench 40 formed by doubling the rod upon itself; and Fig. 6 is a similar view showing the manner in which the socket is formed in the upset head.

As will subsequently appear, the wrench 45 forming the subject matter of this invention is preferably formed from one piece of metal in the form of a rod preferably round in cross section, and is provided with integral handle, shank, and head portions. The handle portions 10, preferably extend laterally from, or at right angles to the shank 11, the handles merging into the shank which is formed by continuations of the handle portions which are joined together forming a 50 shank which is double the size of either handle portion. At the end of the shank op-

posite to the end from which the handles project, is formed the wrench head 12, containing a wrench socket 13. As will subsequently appear, the two portions of the rod 60 forming the shank are preferably welded together when the doubled or closed end of the shank is upset, and though the weld between the two parts of the shank is preferably extended from the wrench head to, or substantially to the point where the parts of the shank diverge to form the handles, nevertheless it is not essential that the two portions forming the shank be thus welded together to the extent stated. 65

In making the wrench I prefer to form at the free end of one of the handles a taper 14, to form a screw-driver, and if desired, one of the handles may have a portion indicated at 10° bent at right angles to the main 70 portion of the handle to form a crank by which the wrench can be quickly turned or spun to quickly remove or set the nut.

This wrench may be formed in different ways but preferably, I start with a rod which 80 is of suitable size, formed of suitable stock cut to the right length, and this rod is preferably bent in the cold to form the handle portions 10, and a double shank which is designated 11^a in Fig. 4, the two portions 85 forming the shank 11^a extending in substantial parallelism from the handle portions to the closed end. Then the double portion of the rod is heated to a welding heat and is clamped between a pair of dies 15, preferably with sufficient pressure to weld together the two parallel parts forming the 90 doubled portion. When it is thus gripped in the dies 15, the closed end projects from the dies, and by a suitable upsetting tool, 95 indicated at 16, a head 17, shown by dotted lines in Fig. 5 is upset thereon. Then the partially formed tool is transferred to dies 18, or to a different portion of the dies 15 which are recessed substantially as shown 100 in Fig. 6, and by a suitable tool 19, a wrench socket of the proper shape is formed in the upset end 17. Preferably a portion 20 of the socket forming tool is extended into the recess receiving the upset end of the shank so 105 as to give a finish to the socketed end of the wrench.

This produces a finished wrench made from one piece of metal in a form such that it is strong and serviceable, but can be very 110 readily manipulated.

The process above described and illus-

trated in the drawing is not claimed herein, but constitutes the subject matter of a companion application filed by me of even date herewith.

- 5 Having described my invention, I claim,
1. A one-piece wrench comprising a shank provided at one end with an integral wrench head, and at the other end with a pair of laterally extending handles, the metal forming the handles having a substantially right angle bend at the end of the shank and for 10 a distance extending along the shank in substantial parallelism, and then being united

to form one substantially solid part which extends to the head.

2. A one-piece socket wrench comprising a substantially circular socketed wrench head, a shank integral with the head and of elongated cross-section, said shank at a distance from the head being divided into 20 handle portions, each of substantially one-half the cross-sectional area of the elongated portion of the shank.

In testimony whereof, I hereunto affix my signature.

ROY H. SMITH.
